(57) **CLAIM**

The ornamental design for a stun gun, as shown and described.

DESCRIPTION

FIG. 1 is a perspective view showing a front end, a left side, and a back side of a stun gun in accordance with this invention.

FIG. 2 is a perspective view showing a rear end, the left side, and the back side of the stun gun of FIG. 1.

FIG. 3 is a top plan view showing a top side of the stun gun of FIG. 1.

FIG. 4 is a right side elevational view showing a right side of the stun gun of FIG. 1.

FIG. 5 is a rear plan view showing the back side of the stun gun of FIG. 1.

FIG. 6 is a front end elevational view showing the front end of the stun gun of FIG. 1; and,

FIG. 7 is a rear end elevational view showing the rear end of the stun gun of FIG. 1.

The broken lines located on the front end of the stun gun in FIGS. 1, 3, 4, 5, and 6 are for the purpose of illustration only, and form no part of the claimed design.
